GAME APPARATUS

Marie S. Mayer, Vineland, N. J., and George W. Schilling, Philadelphia, Pa.

Application February 27, 1936, Serial No. 65,938

8 Claims. (Cl. 273—131)

This invention relates to game apparatus, and more particularly to apparatus for playing a game of the checker type.

The principal object of the present invention is to provide a novel form of game apparatus by means of which interesting games of the checker type may be played.

A further object of the invention is to provide apparatus for playing games of the checker type 10 in the use of which the outcome of the game is not entirely dependent upon the skill of the respective players in that certain elements of chance are involved in the playing of the game.

A further object of the invention is to provide 15 a game board adapted for playing games as aforesaid, which board may be so constructed or arranged that games of longer or shorter duration may be played, as desired by the players.

With the foregoing objects in view, our invention 20 contemplates the provision of a game board of the checker type having several differentiated fields disposed thereon, so that the moves of the checkers may be varied on the several fields.

The invention further contemplates the provision 25 on certain of the squares of the checker board of indicia corresponding to the various cards of a deck of ordinary playing cards, whereby a deck of ordinary playing cards may be used for determining the initial placement of the checkers on the board.

The invention further contemplates the provision 30 of a board made of panels hinged to each other and having playing squares outlined thereon in such manner that a game of shorter duration may be played thereon.

The nature and characteristic features of the invention will be more readily understood when taken in connection with the accompanying drawings forming part hereof, in which

40 Figure 1 is a plan view of the main face of a game board embodying the main features of the present invention;

Fig. 2 is a similar view of the other face of said game board having disposed thereon a layout 45 for playing a game of similar character but of shorter duration;

Fig. 3 is a similar view of the main face of the game board with said board folded, thereby to provide a layout for the playing of a game of still shorter duration;

Fig. 4 is an edge view of the board folded to provide the layout as shown in Fig. 3.

Referring now more particularly to Fig. 1 of the drawings, the layout of the board as there 55 shown comprises 128 squares disposed eight rows

in width and sixteen rows in length. The two rows on each side of the board are of red squares 10 and black squares 11, whereas the four central longitudinal rows are all white squares 12 with the exception of the king row at each end. 5 In the king row at each end the sequence of the red squares is continued from the side rows, as at 10^a and 10^b, and the other two squares as at 12^a and 12^b are left white.

With the exception of the two central trans- 10 verse rows, each of the white squares 12 carries a designation indicative of a playing card in a deck of ordinary playing cards. The two white squares 12^a of the king row at one end preferably 15 carry indicia designating the king of hearts and the king of diamonds, respectively, while the two white squares 12^b of the king row at the other end carry indicia designating the king of spades and the king of clubs, respectively.

The other indicia may be disposed on the 20 respective squares in any preferred manner such, for example, as that shown in Fig. 1 of the drawings. As there shown, the indicia for all of the hearts are arranged consecutively in one longitudinal row, all of the clubs in another longitudinal row, all of the diamonds in another longitudinal row, and all of the spades in another longitudinal row. With the layout as shown in Fig. 1 of the drawings, there are provided indicia for 25 the entire fifty-two cards of a deck of ordinary 30 playing cards.

As shown in Fig. 2 of the drawings, the reverse side of the board is provided with a layout comprising 96 squares disposed eight rows in width and twelve rows in length. This layout is 35 substantially similar to that shown in Fig. 1 of the drawings, with the exception that the indicia in the white squares designate less than a full deck of playing cards, and the indicia there shown is arranged with the several suits of hearts, 40 spades, diamonds, and clubs disposed in diagonal rows, instead of in longitudinal rows as shown in Fig. 1.

It will be noted that in the use of the arrangement as shown in Fig. 2, on the reverse side of 45 the board having a layout as in Fig. 1 on the front face thereof, spaces 14 will be left at each end of the board, in which spaces the rules of the game may be printed, or advertising matter may be displayed thereon if desired.

The board is preferably made of four panels 50 a, b, c, and d hinged to each other as at 13, so that the same may be folded as shown in Fig. 4 of the drawings to present a playing face as shown in Fig. 3. When thus arranged, the lay- 55

out comprises sixty-four squares in all, disposed eight squares in width and eight in length, and, naturally, the indicia which are disposed on the folded-in faces of the board are concealed and 5 not used when the board is in this condition for playing a game of shorter duration.

The ordinary red and black checkers are used in connection with the board, there being provided fifty-two checkers in all, of which twenty-six are red and twenty-six black. A deck of ordinary playing cards may also be used in connection with the board.

The preferred manner of using the board when the same is disposed as shown in Fig. 1 is as follows. The player at one end takes all of the checkers of one color and the player at the other end takes all of the checkers of the other color. The deck of playing cards is then taken and the kings removed therefrom, after which the 10 remaining forty-eight cards of the deck are shuffled and dealt alternately to the two players. Each player then arranges his checkers on the board in accordance with the cards dealt to him, and also places two of his checkers on the two 15 king spaces in his king row. The playing cards are then no longer used. After the checkers are placed on the board in the chance arrangement determined by the cards dealt to each of the players, said checkers may be moved according 20 to any predetermined set of rules, but it has been found that the following method of playing will be found quite satisfactory.

The checkers are moved and jumped on the board in a manner similar to that of the ordinary 25 game of checkers, with the exception, however, that the checkers may be moved on the white squares transversely, longitudinally, and diagonally. It is also preferable to permit the moves on the white squares to be made either 30 one or two squares at a time, at the player's discretion, in either a transverse or a longitudinal direction. However, initially the longitudinal movement of each player's checkers must always 35 be toward the king row of his opponent as in the ordinary game of checkers. As each checker reaches the opponent's king row, it is "crowned", also as in the ordinary game of checkers, after 40 which it is permissible to move the same in any direction. Movements of the checkers are made 45 on and to the white and black squares only. In moving from the field of white squares the termination of the move must be on a black square. All moves in the side marginal rows naturally 50 must be made diagonally.

Jumping may also be done as in the ordinary 55 game of checkers, it, of course, being understood that while the playing is in the field of white squares the jumps may be made either transversely, longitudinally, or diagonally. Whenever 60 a checker is jumped by an opponent's checker, it is forfeited and removed from the board, and whenever all of a player's checkers are thus forfeited he loses the game.

The full length game may be played on the 65 front face of the board, as illustrated in Fig. 1 of the drawings, or a shorter game may be played by turning the board over and using the layout on the reverse side as shown in Fig. 2. A still 70 shorter game may be played by folding the panels of the board as illustrated in Fig. 4 of the drawings and using the exposed faces of the two end panels, as illustrated in Fig. 3. It should, of course, be understood that when one of the layouts as shown in Fig. 2 or Fig. 3 is used, all cards 75 not included in the indicia displayed on the board

are removed from the deck, as well as the kings which preferably are always removed therefrom.

We claim:

1. Game apparatus of the checker type including a game board subdivided into checker squares 5 of three different colors, the squares of one color being disposed in and completely filling a central field extending from the marginal row at one end to the marginal row at the other end, and the squares of the other colors being disposed alternately with respect to each other in sets of rows, one set extending along each side of the central field.

2. Game apparatus of the checker type including a game board subdivided into checker squares 15 of three different colors, the squares of one color being disposed in and completely filling a central field extending from the marginal row at one end to the marginal row at the other end, the squares of the other colors being disposed alternately 20 with respect to each other in sets of rows, one set extending along each side of the central field, and the sequence of one of said colors being continued in the squares in the marginal row at each end.

3. Game apparatus of the checker type including a game board subdivided into checker squares of three different colors, the squares of one color being disposed in and completely filling a central field extending from the marginal row at one end 30 to the marginal row at the other end, the squares of the other colors being disposed alternately with respect to each other in sets of rows with one set on each side of the central field, and the squares in the central field bearing checker locating 35 indicia corresponding to the cards in a deck of ordinary playing cards.

4. Game apparatus of the checker type including a game board subdivided into checker squares of three different colors, the squares of one color being disposed in a central field extending from the marginal row at one end to the marginal row at the other end and filling said field, the squares of the other colors being disposed alternately with respect to each other in 45 two sets of rows with one set on each side of the central field, the sequence of one of said colors being continued in the squares in the marginal row at each end, and the squares in the central field bearing checker locating indicia corresponding 50 to the cards in a deck of ordinary playing cards.

5. Game apparatus of the checker type including a game board subdivided into checker squares of three different colors, the squares of one color being disposed in a central field 55 extending from the marginal row at one end to the marginal row at the other end, the squares of the other colors being disposed alternately with respect to each other in two sets of rows with one set on each side of the central field, and the board comprising a plurality of panels hinged to each other whereby an intermediate portion of the face thereof may be folded under to decrease 60 the effective playing surface.

6. Game apparatus of the checker type including a game board subdivided into checker squares of three different colors, the squares of one color being disposed in a central field 70 extending from the marginal row at one end to the marginal row at the other end, the squares of the other colors being disposed alternately with respect to each other in two sets of rows with one set on each side of the central field, the sequence of one of said colors being continued in the squares 75

in the marginal row at each end, and the board comprising a plurality of panels hinged to each other whereby an intermediate portion of the face thereof may be folded under to decrease the 5 effective playing surface.

7. Game apparatus of the checker type including a game board subdivided into checker squares of three different colors, the squares of one color being disposed in a central field extending from the marginal row at one end to the 10 marginal row at the other end, the squares of the other colors being disposed alternately with respect to each other in rows on each side of the central field, the sequence of one of said colors being continued in the squares in the marginal 15 row at each end, the squares in the central field bearing checker locating indicia corresponding to the cards in a deck of ordinary playing cards, and the board comprising a plurality of panels hinged to each other whereby an intermediate portion of the face thereof 20 may be folded under to decrease the effective playing surface.

8. Game apparatus of the checker type including a game board subdivided into checker squares of three different colors, the squares of one color being disposed in a central field extending from the marginal row at one end to the 5 marginal row at the other end, the squares of the other colors being disposed alternately with respect to each other in rows on each side of the central field, the sequence of one of said colors being continued in the squares in the marginal 10 row at each end, the squares in the central field bearing checker locating indicia corresponding to the cards in a deck of ordinary playing cards, and the board comprising a plurality of panels hinged to each other whereby an intermediate portion of the face thereof 15 may be folded under to decrease the effective playing surface.
